UNITED STATES PATENT OFFICE.

CLARENCE V. ROBERTS AND KENNETH C. FARNSWORTH, OF PHILADELPHIA, PENNSYLVANIA, ASSIGNORS TO ROBERTS AND MANDER STOVE COMPANY, OF PHILADELPHIA, PENNSYLVANIA, A CORPORATION OF PENNSYLVANIA.

DESIGN FOR A GAS HEATER.

60,172.

Specification for Design.

Patented Jan. 3, 1922.

Application filed May 14, 1921. Serial No. 469,574. Term of patent 14 years.

To all whom it may concern:

Be it known that we, CLARENCE V. ROBERTS and KENNETH C. FARNSWORTH, citizens of the United States, residing in Philadelphia, Pennsylvania, have invented a new, original, and ornamental Design for a Gas Heater, of which the following is a specification, reference being had to the accompanying drawing, forming part thereof, in which the figure

is a perspective view of a gas heater illustrating our new design.

The radiants form no part of the design.

We claim:

The ornamental design for a gas heater, substantially as shown.

CLARENCE V. ROBERTS.
KENNETH C. FARNSWORTH.
